UNITED STATES PATENT OFFICE.

JOHN J. MACEK, JR., OF CHADRON, NEBRASKA.

CHISEL HOLDER.

Application filed May 6, 1925. Serial No. 28,342.

To all whom it may concern:

Be it known that I, JOHN J. MACEK, Jr., a citizen of the United States, residing at Chadron, in the county of Dawes and State of Nebraska, have invented certain new and useful Improvements in Chisel Holders, of which the following is a specification.

The present invention relates to a device for holding a chisel, and has for its principal object to provide a structure which is efficient in holding a chisel for severing the nuts on bolts which hold the angle-bars or fish-plates to the rail. Ordinarily, a man is employed to hold the chisel, while the sledge is being used, and this man is in considerable danger for various obvious reasons. The present holder eliminates this man and holds the chisel in proper position for engaging the nut or square end of the bolt.

Another important object of the invention is to provide a holder of this nature, which is adjustable so that it may be easily engaged with the rail.

A further object of the invention is to provide a device of this nature which is simple in its construction, strong, durable, reliable, easy to manipulate, and well adapted to the purpose for which it is designed.

With the above and numerous other objects in view, as will appear as the description proceeds, the invention resides in certain novel features of construction, and in the combination and arrangement of parts, as will be hereinafter more fully described and claimed.

In the drawing:

Fig. 1 is a side elevation of the device, embodying the features of my invention;

Fig. 2 is a top plan view thereof;

Fig. 3 is a transverse section therethrough, taken substantially on the line 3—3 of Fig. 2, looking in the direction of the arrows;

Fig. 4 is a fragmentary elevation, showing particularly the nut-engaging member; and

Fig. 5 is a sectional view through the clamp, showing the handle of the chisel mounted therein.

Referring to the drawing in detail, it will be seen that 1 designates a plate which is adapted to rest on top of the rail and extend longitudinally therewith. A pair of spaced parallel standards 2 rise from the

plate 1. A bolt or pin 3 extends transversely across the upper ends of the standards 2. A plate 4 has one end rolled, as at 5, so as to rotatably engage the bolt 3. The other end of this plate 4 is curved arcuately as at 6 to form a clamp section. Another clamp section 7, of arcuate formation, is pivoted as at 8 to the clamp section 6, and has an extension 9 for receiving a bolt 10 piercing the plate 4. The nut 11 is engaged with the bolt, for engaging the sections 6 and 7 about the handle 12 of the chisel 13.

A pair of standards 14 rise from the base-plate 1 and are spaced longitudinally thereof and receive between the upper ends thereof a handle bar 15. A pair of L-shaped engaging members 16 and 17 are disposed adjacent the standards 2, on the plate 1. The member 17 includes the horizontal portion 18, which is corrugated on its surfaces and provided with a pair of slots 19, and a vertically extending portion 20, which is provided with a pair of spaced apertured ears 21 and 22, for receiving the pin 23, the under edge of the ear 21 being provided with a notch 24. An arm 25 is pivotally engaged by means of a sleeve 26 to the pin 23, and the extremity thereof is provided with a recess 27. The upper edge of the sleeve 26 is provided with a lug 28. A spring 29 is coiled about the pin 23, between the ear 22 and the sleeve 26, and one end thereof engages the portion 20, while the other end thereof engages the arm 25 as at 30, and normally holds the arm in the positions shown in Figs. 2 and 4. This arm, however, may be swung to a position at right angles to that shown in Figs. 2 and 4, at which time the lug 28 will engage in the notch 24, and thus hold the spring 29 under tension. The nut to be severed is to rest in the recess 27, as is shown to advantage in Fig. 1 and will thus be prevented from turning. The member 16 includes a horizontal portion 32 and a vertical portion 33. The horizontal portion 32 is corrugated on its lower surface for cooperating with the corrugating upper surface of the portion 18. The horizontal portion 32 is also provided with a pair of slots 34 which are adapted to be placed in registry with slots 19, so that screws 35 and 36 may be passed therethrough and engaged in the plate 1, and thus the portions 18 and 32 may be held in adjusted positions in relation to the plate

1, for the purpose of varying the distance between the portions 20 and 33. The portion 33 is provided with a longitudinally extending slot 37. A bowed member 38 is pivoted in the lower end of the slot 37 as at 40, and is provided with an extension 41, which is disposed under the handle bar 15, so that the bowed portion may be swung out of the slot 37 and out of engagement with 45 the fish plate. A spring 42 is engaged at one end with the screw 36 and at the other end with the upper portion of the bowed member 38 and normally holds this bowed member in the position shown in Fig. 3.

15 A pair of members 44 and 45 are provided at the other end of the plate 1 and are similar in construction to members 16 and 17, except that member 45 is not provided with the ears 21 and 22 and associated parts, 20 and the bowed member of the member 45 is not provided with the extension 41. Furthermore, members 44 and 45 are not quite as large as members 17 and 16 respectively. These members 16, 17, 44 and 45 are adapted 25 to engage the fish-plates or the sides of the tread of the rail, so as to hold the base-plate in position on the rail, so that the chisel may be engaged with the nut disposed in the recess 27 of the arm 25. When thus disposed, it will be seen that the sledge may be struck against the chisel for severing the nut from the bolt as is usual. This will 30 eliminate the necessity of having a separate man for holding the chisel and will eliminate the dangers incident to such a man holding the chisel.

It is thought that the construction, oper-

ation, and advantages of this invention will now be clearly understood by those familiar with the use of chisels of this nature, without a more detailed description thereof. It is desired, however, to point out that the present embodiment of the invention has been disclosed merely by way of example, and that numerous changes in the details 45 of construction, and in the combination and arrangement of parts may be resorted to, without departing from the spirit or scope of the invention as hereinafter claimed or sacrificing any of its advantages. 50

Having thus described my invention, what I claim as new is:

In a structure of the class described, a plate, a pair of adjustable members mounted on the plate and having depending portions, one of said depending portions being slotted vertically, a bowed member hingedly mounted in the slot, a spring for normally holding the bowed member extended inwardly of the slot, the other depending portion provided with a pair of apertured ears, a pin extending through the apertured ears, an arm slidably and rotatably mounted on the pin and provided with a recess for engaging the nut, and a spring on the pin 65 for engaging the arm to hold it in a raised position for engaging the under side of the nut, and clamping means pivotally engaged with the plate for holding a chisel in engagement with the nut supported in the 70 arm.

In testimony whereof I affix my signature.

JOHN J. MACEK, Jr.
